UNITED STATES PATENT OFFICE.

EMIL GNOETH, OF CINCINNATI, OHIO, ASSIGNOR TO THE INTERNATIONAL HARNESS MACHINERY COMPANY, OF CINCINNATI, OHIO, A CORPORATION OF OHIO.

LOOP-FORMING PRESS.

1,285,680.

Specification of Letters Patent.

Patented Nov. 26, 1918.

Application filed June 17, 1918. Serial No. 240,401.

To all whom it may concern:

Be it known that I, EMIL GNOETH, a citizen of the United States, residing at Cincinnati, in the county of Hamilton and State of Ohio, have invented a new and useful Improvement in Loop-Forming Presses, of which the following specification is a full disclosure.

My invention relates to an improvement 10 in forming presses of the hand operated type, and is more particularly directed to a forming press adapted for use in forming and compressing harness strap loops.

The object of the invention is to provide 15 a press of this type with automatic compensating operating mechanism having a compound power stroke and operated by a single lever.

Another object is to provide a yielding 20 mandrel for centering the work in relation to the compression members.

Other objects and features are more fully set forth in the description of the accompanying drawings, forming a part of this 25 specification, in which:—

Figure 1 is a front elevation, partly in section, the mechanism being in normal position.

Fig. 2 is a top plan view, partly in section.

Fig. 3 is a vertical section on line 3, 3, of Fig. 1.

Fig. 4 is a front elevation with the parts in operated position and the work in position.

Fig. 5 is a perspective view of a harness strap with completed strap loop.

When the strap and loop, as shown in finished form in Fig. 5, are assembled and 40 stitched, the loop assumes a rounded form, as shown in dotted lines, and as in the finished product it is desired to produce a loop of approximate flat rectangular form, a compressing or molding of the loop is required. This operation is also utilized to 45 form finish stripes, beadings or other decorative borders or markings, as may be desired.

The press comprises a frame 1, having its 50 upper part cored out to form front and rear walls 2, 3, and its medial portion horizontally slotted to provide a slide-way for a pair of reciprocating side die blocks 4, 4. Said die-blocks are provided with detachable side dies 5, 5, and are guided through-

out their movements by rods 6, 6, each extending through a bore in the frame. These rods are provided with abutment heads 7, 7, and between these heads and the frame, I provide coil springs 8, 8, which exert a 60 strong normalizing influence on the rods and die-blocks.

An anvil die or plate 9 is centrally positioned in a recess in the frame intermediate the opposing side dies and a top die 10 is 65 detachably secured to the under face of a vertically reciprocating plunger 11. Said plunger is slidably mounted in slots cut in the front and rear walls 2, 3. Adjacent either side of the plunger 11 and slidably 70 mounted in ways formed in the walls 2, 3, there is provided a pair of side die operating slides 12, 12, each slide being apertured near its lower end to receive one end of a bell crank lever 13, the opposite end of 75 which pivotally connects with its companion side die block 4. The bell crank levers 13, 13, are pivoted between the walls 2, 3, on studs 14, 14. A pair of spring receiving apertures 15, 15, are cut, half in each of the 80 abutting surfaces of the plunger 11 and the side die operating slides 12, 12, forming opposing abutments for the springs 16, 16. These springs are relatively weaker than the springs 8, 8, but are of sufficient power 85 to return the plunger 11 to normal position.

An operating hand lever 17 is eccentrically journaled on a shaft 18 mounted in the upper ends of the operating slides 12, 12, the eccentric cam portion 19 of said handle 90 being adapted to engage the plunger 11. 20 represents a floating work supporting mandrel which is detachably secured to a yielding spring arm 21. The forward end of the mandrel is rounded to facilitate the threading 95 of the work thereon. The arm 21 is fixed to the frame 1 and extends upwardly to form a stop 22 for the operating lever 17.

In the operation of the press, the work is threaded on the mandrel 20 positioning the 100 strap loop 25 intermediate the dies. The hand lever 17 is then pulled forward, its eccentric cam portion 19 engaging and forcing downward the plunger 11 until the top die engages the strap loop 25 on the mandrel 105 20 and forces the strap against the anvil die 9. This forms an abutment limiting the downward movement of the plunger 11, except for a final compressing operation, as will be later explained. During the plun- 110

ger movement, just described, the springs 8, 8, being of greater strength than the springs 16, 16, hold the side die blocks 4, 4, in normal position against the frame 1 and 5 by the intervening bell crank levers 13, 13, likewise hold the slides 12, 12, against movement during the compressing of the springs 16, 16. In this instance the lever 17 pivots on the slides 12, 12, and the plunger is the 10 driven member. When the plunger reaches the end of its stroke and the hand lever 17 is further operated, the cam portion 19 thereof, using the plunger 11 as a pivot abutment, exerts an upward pull on the shaft 18 and 15 slides 12, 12. This upward movement of the slides 12, 12, will rock the bell crank levers 13, 13, and force the side die blocks 4, 4, inwardly bringing their dies 5, 5, into engagement with the strap loop 25. In this instance, the plunger 11 is the pivot of the 20 lever and the slides 12, 12, the driven members.

With all the dies engaging the loop, a final pressure is applied to the hand lever 17 25 to compress the loop and impress the finish stripes or beadings into the leather surface.

By this arrangement, I have provided a compression press having a compound power stroke which automatically compensates for 30 variations in thickness and quality of the leather stock operated upon.

Having described the invention, I claim:—

1. A device of the class described comprising a frame, translatory side die members, a plunger, a top die carried thereby, reciprocatory side die operating members, and an operating lever pivotally mounted on the operating members and engaging the plunger.
2. A device of the class described comprising a frame, translatory side die members, a plunger, a top die carried thereby, reciprocatory side die operating members, spring means intermediate the plunger and 45 operating members, for normalizing the

plunger, spring means for retaining the side die members in normal position until the plunger has completed its power stroke, and an operating lever pivoted on the operating members and engaging the plunger.

50

3. A device of the class described comprising a frame, an anvil plate, translatory side dies, a plunger, a top die carried thereby, a floating work supporting mandrel positioned intermediate the dies and anvil plate, reciprocatory side die operating members, and an operating lever pivoted on said members and engaging the plunger.

55

4. A device of the class described comprising a frame, translatory side dies, a plunger, a top die carried thereby, reciprocatory side die operating members, an operating lever pivoted on the operating members and engaging the plunger adapted to first reciprocate said plunger in one direction and subsequently reciprocate the side die operating members in a reverse direction, spring means for normalizing the plunger, and a second spring means for normalizing the side dies.

60

5. In a device of the class described, a frame, side dies and an intermediate top die, a plunger and lever first operating the top die, and means operated by the lever for actuating the side dies while the top die is 75 in position of pressure.

6. In a device of the class described, a frame, an anvil block and floating mandrel, side and top dies adapted to close in relation to the anvil and mandrel, and a die 80 operating mechanism having a common operating member, for sequentially operating the top and then the two side die members.

In witness whereof, I hereunto subscribe my name, as attested by the two subscribing 85 witnesses.

EMIL GNOETH.
